DOLL OR THE LIKE

Elizabeth Raines, Beverly Hills, Calif.

Application July 13, 1953, Serial No. 25,920

Term of patent 14 years

(Cl. D34—2)

FIG. 1

To all whom it may concern:

Be it known that I, Elizabeth Raines, a citizen of the United States, residing at Beverly Hills, in the county of Los Angeles in the State of California, have invented a new, original, and ornamental Design for a Doll or the like, of which the following is a specification, reference being had to the accompanying drawings, forming a part thereof.

I claim:

The ornamental design for a doll or the like, as shown.
